(57) **CLAIM**

The ornamental design for a grate, as shown and described.

DESCRIPTION

FIG. 1 is a top perspective view of a second embodiment of the grate of the new design;

FIG. 2 is a bottom perspective view of the grate of FIG. 1;

FIG. 3 is a top plan view of the grate of FIG. 1;

FIG. 4 is a bottom plan view of the grate of FIG. 1;

FIG. 5 is a front elevational view of the grate of FIG. 1, the rear elevational view being a mirror image of the grate of FIG. 5; and,

FIG. 6 is a right side elevational view of the grate of FIG. 1, the left side elevational view being a mirror image of the grate of FIG. 6.

The portions of the Figures shown in broken lines are not part of the claimed design and are for illustration only.
